UNITED STATES PATENT OFFICE

159,170

CASING FOR A MINE-LAMP BATTERY OR SIMILAR ARTICLE

Willson Y. Stamper, Newark, N. J., assignor to
Thomas A. Edison, Incorporated, West Orange,
N. J., a corporation of New Jersey

Application July 13, 1949, Serial No. 3,873

Term of patent 14 years

(Cl. D26—6)

To all whom it may concern:

Be it known that I, Willson Y. Stamper, a citizen of the United States and a resident of the city of Newark, county of Essex, and State of New Jersey, have invented a new, original and ornamental Design for a Casing for a Mine-Lamp Battery or Similar Article, of which the following is a specification, reference being had to the accompanying drawings, forming a part thereof.

In the drawing:

Figure 1 is one side elevational view of a casing for a mine-lamp battery showing my new design;

Figure 2 is the other side elevational view thereof;

Figure 3 is a top plan view thereof;

Figure 4 is one end elevational view thereof; and

Figure 5 is the other end elevational view thereof.

I claim:

The ornamental design for a casing for a mine-lamp battery or similar article, substantially as shown.

WILLSON Y. STAMPER.
